JUG

George W. Worthington, Castro Valley, Calif., assignor
to Owens-Illinois Glass Company, Toledo, Ohio, a cor-
poration of Ohio

Filed June 25, 1962, Ser. No. 70,662

Term of patent 14 years

(Cl. D58—5)

FIG. 1 is an elevational view of a jug showing my new design, the ornamental detail being continuous around the jug and the opposite side being the same.

FIG. 2 is a top plan view thereof.

The characteristic features of my design for the jug disclosed reside in the relatively closely spaced annular ribs in the shoulder area spanning the handle of the jug and the relatively widely spaced annular grooves in the area below the handle, and the top, having the configurations as shown.

I claim:

The ornamental design for a jug, substantially as shown and described.
